UNITED STATES PATENT OFFICE

2,280,951

HIGHWAY SIGNAL

Okla H. Hershman, Indianapolis, Ind.

Application October 13, 1939, Serial No. 299,249

14 Claims. (Cl. 40—130)

The present invention, in some of its aspects, is an improvement on the signal or sign described in my prior Patent No. 2,113,759, and like the invention of such prior patent, relates to flexible chains adapted to be applied to supporting panels to delineate signs or signals. Usually, the links of such a chain carry light-reflecting elements or "buttons" which, owing to the flexibility of the chain, can be arranged in any desired pattern and secured to a suitable supporting panel.

It is the object of my present invention to increase the flexibility and possibilities of use of such a chain and, at the same time, to simplify and cheapen its manufacture.

In carrying out the present invention, each link of the chain is formed of two elements pivotally interconnected about the axis of the light-reflecting button or equivalent element. The several links are interconnected together through pivotal and slotted connections, the pivotal character of the connection permitting the chain to be arranged in any predetermined pattern and the slotted character of the connection permitting variation of the distance between adjacent buttons. Conveniently, the two elements forming each link of the chain are made of sheet-metal and have interfitting circular body portions. One element of each link is provided with a radially projecting elongated ear having a radially extending slot, and the other element is provided with another ear having a boss received in the slot of the elongated ear of the adjacent link.

The accompanying drawing illustrates my invention: Fig. 1 is a plan view of one form of chain in which my invention has been embodied; Fig. 2 is a longitudinal section through the chain shown in Fig. 1; Figs. 3 and 4 are plan views respectively of the two elements making up each link of the chain shown in Figs. 1 and 2; Figs. 5 and 6 are sections through the two link-elements of Figs. 3 and 4 respectively; Fig. 7 is a section illustrating a modified form of element corresponding to the element shown in Figs. 4 and 6; Figs. 8 and 9 are plan views of the two link elements making up a chain embodying a modified form of light-reflecting element; Figs. 10 and 11 are sections through the two link elements shown in Figs. 8 and 9 respectively; Fig. 12 is a sectional view on a somewhat enlarged scale showing the element of Figs. 8 and 10 assembled with the element of Figs. 9 and 11; Fig. 13 is a view similar to Fig. 12 but illustrating a construction suitable for use with still a differ-

ent form of light-reflecting unit; Fig. 14 is a plan view of a modified form of the invention employing a different method of interconnecting adjacent links; Fig. 15 is a side elevation of the link shown in Fig. 14; Fig. 15a is a transverse section through a chain made up of the links shown in Figs. 14 and 15; Fig. 16 is a section through a modified form of link element which can be substituted for that illustrated in Figs. 3 and 5; and Fig. 17 is a plan view showing the rear of the chain illustrated in Figs. 1 and 2 modified to hold the various links in a straight line.

The chain illustrated in Figs. 1 to 6 comprises a plurality of links each of which is made up of two associated elements 20 and 21. The element 20 has a generally ring-like body portion provided on one face with an inwardly extending annular flange 25. At the opposite face, the body portion is provided with an ear 26 which extends radially outwardly, as is clear from Figs. 3 and 5.

Each of the elements 21 likewise has a generally ring-like body portion having at one face an inwardly extending annular flange 27 and at the other face an ear 28 which projects radially outwardly. The ear 28 is relatively long and is provided with an elongated slot 29, the material removed in the formation of which may be bent inwardly over the cup to form a tongue 30.

The dimensions of the body portion of each element 21 are such as to permit it to receive a light-reflecting element of its equivalent. In Figs. 1 and 2, I have shown light-reflecting elements in the form of glass disks 32 the front face of each of which is provided with a multiplicity of generally hemispherical projections and the rear face of which is silvered or otherwise rendered of light-reflecting character. If, desired, each of the buttons 32 may be received in a cup 33 of soft rubber or other suitable material which protects the rear face of the elements from attack by the elements and also tends to prevent breakage. The button 32 is held in place in the link-element 21 by the tongue 30.

For the purpose of holding the two elements of each link together, the annular flange 27 of each of the link-elements 21 may be provided with a plurality of ears 34 which are formed originally as inward extensions of the flange 27 but which, after assemblage, are bent outwardly over the flange 25 of the associated link-element 20.

Means are provided for pivotally interconnecting the ear 26 of each link with the longer ear

28 of an adjacent link. This may conveniently be done by extruding the central portion of each of the ears 26 into a boss 35 of such a diameter as to be received within the slot 29 in the ear 28 of the adjacent link and by turning the edge of such extruded boss outwardly to form a flange 36. The slot 29 may be widened as indicated at 29' adjacent the body portion of each of the elements 21 to permit passage of the flange 36. In assembling a chain of links so formed, the flange 36 of one link is passed through the widened slot-portion 29' of the adjacent link, and the two links are then moved apart so that the boss 35 will be received in the narrower portion of the slot 29. Alternatively, formation of the flange may be deferred until after the boss 35 has been passed through the slot 29. If this slot is widened as indicated at 29', I prefer to place the boss 35 far enough from the outer end of the ear 26 that the boss cannot enter the widened slot-portion 29' unless the two adjacent links are swung into approximately perpendicular relationship.

A chain such as has been described is exceedingly flexible and possesses wide possibilities of use. Each link may be swung angularly to any desired position about the axis of the boss 35 of the adjacent link; and, in addition, the spacing between adjacent light-reflecting buttons or equivalent elements can be varied by sliding the bosses 35 in the slots 29. If desired, each of the link-elements 20 may be provided opposite the ear 26 with a second ear 39 provided with an opening 40. The chain may be held against a supporting panel 41 by means of nails or screws 42 which pass into the panel through the bosses 35, through the slots 29, or through the holes 40 in the ears 39.

If, for any reason, it is desired to limit the possibilities of movement of adjacent elements in the chain, the ends of one or more of the tongues 38 may be bent outwardly through the slots 29 overlapping them, as indicated at 30' in Fig. 17.

In the arrangement illustrated in Figs. 1 to 6 inclusive, I have shown the central portion of each chain element as a substantially complete ring or cup, but this is not essential. Thus, I may substitute for each link-element 21 a link-element 21' such as is illustrated in Fig. 7 and in which the major portion of the body of the central part is eliminated to leave only the flange 27 with its ears 34. Such a chain element can be assembled with the chain element 20 to form a complete link, the bearing between the two chain elements being formed by the out-bent ears 34. Or, instead of eliminating the major portion of the body of each of the link-elements 21, I may do the same thing with each of the link-elements 20, as indicated in Fig. 17. Here, the body portion of the link-element 21' is restricted to the flange 25. A link-element 20' may be used with a link-element 21, the fingers 34 on the latter, when bent outwardly over the flanges 25, serving to interconnect the two link-elements pivotally.

In the arrangement illustrated in Figs. 8 to 12 inclusive, I have illustrated chain-elements adapted to use a different form of light-reflecting unit. In the chain of Figs. 8 to 12, each link is formed of two intersecting elements 50 and 51. The element 50 is formed with a frusto-conical body portion 52 provided with the laterally extending ear 26 equipped with the flanged boss 35. The central portion of the element 51 is in the form of a disk having its central portion 75

dished as indicated at 53 and provided with the slotted tongue 28. Around the periphery of the dished portion 53 of each of the elements 51 there extends an annular series of ears 54.

5 The link-elements, or at least each link element 51, is formed of bright metal so that the inner face of each dished central portion 53 will possess light-reflecting properties. In the assembled chain, each of the dished central portions 10 53 contains a plurality of glass beads 55 held in place by a transparent cover 56. In assembling 15 the chain, the glass beads are put in place, covered by the cover 56, and alternate ones of the ears 54 are bent inwardly over the periphery of the cup to secure it in position. The remaining ears 54 are bent inwardly to an extent sufficient 20 to permit them to pass through the frusto-conical central portion 52 of the chain element 50, and the ends are then bent outwardly over that frusto-conical portion 52 as indicated at the right in Fig. 12.

The chain illustrated in Fig. 13 is one which is adapted to carry relatively deep light-reflecting buttons. Each of such buttons comprises a 25 lens-like glass body 60 and a cup-like casing 61 therefor. This casing is provided adjacent its open end with an exterior annular flange 62 and, at its opposite end, with a threaded stud 63.

The chain link in which each button 60-61 30 is mounted is formed of two parts 64 and 65, generally similar respectively to the two parts 20 and 21 of the chain illustrated in Figs. 1 to 6, but having central body portions deep enough to receive the button-housing 61. The two elements of 35 each link are held in assembled relation and the associated button 60-61 in place therein by means of a cup 66 which surrounds the button-housing 61 and the open end of which bears against the inner surface of the flange 27 on the link-element 65, the cup being retained in position by a nut 64 on the stud 63.

The link illustrated in Figs. 14 and 15 consists of two elements 70 and 71 respectively similar to the elements 20 and 21 of Figs. 1 to 6. Instead of 45 an ear similar to the ear 26, however, the link-element 70 is provided with an ear 72 which is bent downwardly and slotted at its sides as indicated at 73. The elongated ear 28 on the link-element 71 is provided with a slot 74 having a width substantially equal to the distance between the bottoms of the two notches 73 in the ears 72. In assembling links of the type illustrated in Figs. 50 14 and 15, one link is placed at right angles to the other and the ear 72 passed through the slot 74. Upon bringing the two links into approximate alignment, the sides of the ear 28 enter the slots 73 and prevent separation of the links.

I claim as my invention:

60 1. In a device of the class described, a series of interconnected links, each of said links comprising a pair of interfitting relatively rotatable cups, a light-reflecting element mounted in the inner one of said cups, each of said cups being provided with a radially projecting ear, and means pivotally interconnecting ears on adjacent links, one of the ears so interconnected being provided with an elongated slot in which the interconnecting means is received, said slot having a widened portion through which said interconnecting means may be withdrawn.

65 2. In a device of the class described, a series of interconnected links, each of said links comprising a pair of interfitting relatively rotatable cups, a light-reflecting element mounted in the inner one of said cups, each of said cups being

provided with a radially projecting ear, and means pivotally interconnecting ears on adjacent links, one of the ears so interconnected being provided with an elongated slot in which the interconnecting means is received, said cups and ears being formed of sheet metal and said slot being formed by removal of a tongue of metal which is bent inwardly of its associated cup and over the light-reflecting element therein.

3. In a device of the class described, a series of interconnected links, each of said links comprising a pair of interfitting relatively rotatable cups, a light-reflecting element mounted in the inner one of said cups, each of said cups being provided with a radially projecting ear, and means pivotally interconnecting ears on adjacent links, one of the ears so interconnected being provided with an elongated slot in which the interconnecting means is received.

4. In a device of the class described, a series of interconnected links, each of said links comprising a pair of relatively rotatable members, a light-reflecting element mounted in one of said members at their axis of relative rotation, each of said members being provided with a radially projecting ear, and means pivotally interconnecting ears on adjacent links, one of the ears so interconnected being provided with an elongated slot in which the interconnecting means is received, said slot having a widened portion through which said interconnecting means may be withdrawn.

5. In a device of the class described, a series of interconnected links, each of said links comprising a pair of relatively rotatable members, a light-reflecting element mounted in one of said members at their axis of relative rotation, each of said members being provided with a radially projecting ear, and means pivotally interconnecting ears on adjacent links, one of the ears so interconnected being provided with an elongated slot in which the interconnecting means is received.

6. In a device of the class described, a series of interconnected links, each of said links comprising a pair of relatively rotatable members, a light-reflecting element mounted in one of said members, each of said members being provided with a radially projecting ear, and means pivotally interconnecting ears on adjacent links, one of the ears so interconnected being provided with an elongated slot in which the interconnecting means is received.

7. In a device of the class described, a series of interconnected links, and light reflecting elements carried by said links, each of said links

having a pair of outwardly extending ears of sheet-metal one of which is provided with an opening extending therethrough, the other of said ears being provided with a boss received in the opening of an adjacent link, said boss being integral with the associated arm and having at its outer end an integral flange of a diameter larger than the width of such opening in the adjacent link.

8. The invention set forth in claim 7 with the addition that said opening is an elongated slot and has a widened portion through which said flange may be passed to permit the separation of adjacent links.

9. The invention set forth in claim 7 with the addition that said opening is an elongated slot.

10. In a device of the class described, a series of interconnected links, and light reflecting elements carried by said links, each of said links having a pair of outwardly extending ears one of which is provided with an elongated slot and the other of which is provided with means pivotally and slidably received in the slot of an adjacent link.

11. The invention set forth in claim 10 with the addition that said slot is provided with a widened portion through which said means may be withdrawn.

12. The invention set forth in claim 10 with the addition that said slotted ear is of sheet metal, the slot therein being formed by removal of a tongue of metal which is bent over the associated light-reflecting element to retain it in place in the link.

13. In a device of the type described, a series of link members, means pivotally connecting adjacent link members together, and light-reflecting elements associated with at least alternate ones of said pivotally-connecting means, at least alternate ones of said link members being provided respectively with longitudinal slots for slidably receiving the associated pivot means whereby the distance between adjacent light-reflecting elements may be varied.

14. In a device of the type described, a series of link members, means pivotally connecting adjacent link members together, and light-reflecting elements associated with alternate pivotally-connecting means, one of the two link members pivotally interconnected by each of the remaining pivotally-connecting means being provided with a slot for slidably receiving the associated pivot means whereby the distance between adjacent light-reflecting elements may be varied.

OKLA H. HERSHMAN.
